UNITED STATES PATENT OFFICE.

ORSON A. WOOLLEY, OF SALT LAKE CITY, UTAH.

COPY-HOLDER.

SPECIFICATION forming part of Letters Patent No. 636,423, dated November 7, 1899.

Application filed November 8, 1898. Serial No. 695,407. (No model.)

To all whom it may concern:

Be it known that I, ORSON A. WOOLLEY, a resident of Salt Lake City, in the county of Salt Lake and State of Utah, have invented certain new and useful Improvements in Copy-Holders; and I do hereby declare the following to be a full, clear, and exact description of the invention, such as will enable others skilled in the art to which it appertains to make and use the same.

My invention relates to an improvement in copy-holders, the object of the invention being to provide a device which will operate to firmly and securely hold a book or other copy in position to be readily copied.

A further object is to provide a copy-holder which can be readily adjusted to accommodate different-sized articles and to provide means whereby to enable a copyist to readily follow the copy.

A further object is to provide a device of the above character which will be simple in construction, neat in appearance, easily operated, and most useful and serviceable.

With these objects in view the invention consists in certain novel features of construction and combinations and arrangements of parts, as will be more fully herein-after described, and pointed out in the claims.

In the accompanying drawings, Figure 1 is a front view of my improved holder. Fig. 2 is a side view. Fig. 3 is a rear view of same, and Fig. 4 is a detail.

1 represents a rectangular frame having its bottom member extended laterally beyond the sides of the frame, as shown at 2. A solid block 3 is disposed in the frame 1 and is secured to the top and bottom pieces thereof. The block 3 is preferably narrower than the frame 1, and thus leaves an open space between each side of block 3 and the side of the frame 1, and the sides of the plate and frame are connected by horizontal rods or braces 4.

Legs or supports 5 are secured to the side pieces of the frame and are each secured between their ends to one end of the extended portions 2 of the bottom section of the frame and then extend downward any desired distance, according to the height desired for the holder, and said legs are provided at their lower ends with flat bearing-plates 6, whereby to more firmly support the holder in place.

The plates 6 may be provided with holes or openings for the reception of suitable screws or nails 7, whereby to secure the device against 55 movement.

Legs or supports 8 are hinged to the rear faces of the sides of the frame 1 by means of loose-pin hinges a, and in constructing these legs or supports I prefer to provide them, 60 near their upper ends, with brace-arms 10, also pivoted to the hinges a.

It will be understood that I do not wish to limit myself to hinging the legs or supports 8 to the rear of the frame, as I may hinge the 65 same to the rear of the legs or supports 5.

A bracket or support 11, comprising a top plate 12, having downwardly-extending arms 13 at its ends, is secured to the bottom piece 2 of the frame 1, and said arms 13 are provided on their upper edges with notches or recesses 15, as shown. The plate 12 serves to receive a book of any ordinary thickness placed thereon.

A follower-frame 16 is provided and consists of two upright arms 17, connected at their lower ends by a cross-bar 18, and said uprights may, if desired, be connected at their upper ends by means of a cross-bar 19. Sleeves 20 at the ends of a follower 21 are 80 mounted on the upright arms 17 and are adapted to be moved thereon. The cross-bar 18 is disposed at each end in one of the notches or recesses 15 in the blocks 14 and is provided with coiled springs 22, having 85 one end secured to the cross-bar 18 and the other end free to bear against the top plate 12, whereby to hold the cross-bar in the notches or recesses and at the same time force the follower-frame against the copy. The upper 90 ends of the arms 17 are bent to form enlargements to prevent injury to the book or other copy supported on the holder.

It will be readily seen that when it is desired to adjust the follower-frame to accommodate copies of different thicknesses it is simply necessary to raise the follower-frame until the cross-bar 18 is free of the notches or recesses 15 in which it is disposed and move the same to other notches or recesses 100 in the blocks 14, when the springs 22 will securely hold the same therein.

A bar or strip 23, having a downwardly-projecting pin 24 at or near each end, is mounted

on the top section of the frame 1, and the pins 24 are disposed in openings or holes in said top section and extend through said section a desired distance. Coiled or other springs 5 25 are disposed on said pins 24, whereby to yieldingly hold the rod or strip 23 a short distance from the top section of the frame.

When it is desired to support a note-book on the holder, it is simply necessary to raise the 10 bar or strip 23 and slip the cover and more or less of the pages of the open note-book under said bar, when the latter will be drawn down on the book by the springs 25 and secure the same in the desired position for copying.

15 When it is desired to secure a book or copy-sheet in position, it is simply necessary to pull the arms 17, carrying the follower 21, outward and place the book or sheet on the plate 12 and then permit the arms 17 and follower 20 lower to be forced back against the book or sheet by means of the springs 22. When the follower is in this position, it can be readily raised to the top line of the copy, and as each line is copied the follower can be moved 25 down to the next succeeding line, and so on throughout the copy, and when it is desired to remove the copy it is simply necessary to pull the arms 17 and follower 21 outward, when the book or sheet can be readily removed 30 and the copy-holder will be ready for another copy.

Various slight changes might be resorted to in the general form and arrangement of the several parts described without departing 35 from the spirit and scope of my invention, and hence I would have it understood that I do not wish to limit myself to the precise details set forth, but consider myself at liberty to make such slight changes and alterations 40 as fairly fall within the spirit and scope of my invention.

Having fully described my invention, what I claim as new, and desire to secure by Letters Patent, is—

45 1. The combination with an upright frame and outwardly-projecting bracket or shelf projecting from the lower part of said upright frame, of an open frame pivotally connected with said bracket or shelf, means for

adjusting the pivotal attachment of said open 50 frame to the bracket toward and away from the upright frame, a spring connected with said bracket, shelf and the pivoted frame and normally pressing the latter against the upright frame and a follower mounted to slide on 55 the pivoted frame, substantially as set forth.

2. The combination with an upright frame and arms projecting outwardly from said frame and each having a series of notches, a hinged frame disposed in front of said upright frame and having a horizontal member mounted in said notched arms, a spring pressing said hinged frame toward the upright frame and a follower mounted to slide on said hinged frame, substantially as set forth. 60 65

3. The combination of an upright frame, a shelf at the lower end thereof, a bar disposed over said frame and springs connected with both of the ends of said bar and the frame, substantially as set forth. 70

4. The combination of an upright frame having an opening therein, a solid block or plate closing said opening, a shelf below said block or plate, a bar above the frame, pins depending from said bar and passing loosely 75 through the top of said frame at points laterally beyond the solid block or plate, nuts on said pins and springs encircling said pins and bearing at their respective ends against the frame and said nuts. 80

5. The combination with a frame, of a bracket secured to said frame comprising a top plate, depending arms at each end of said plate, blocks having notches or recesses therein secured between said depending arms at 85 each end of said plate, a follower-frame having a cross-bar at its lower end disposed in the recesses or notches in each block and a spring secured to said cross-bar and adapted to bear against said top plate. 90

In testimony whereof I have signed this specification in the presence of two subscribing witnesses.

ORSON A. WOOLLEY.
